MAX HERMSDORF, OF ESSEN-ON-THE-RUHR, GERMANY, ASSIGNOR TO FRIED. KRUPP AKTIENGESELLSCHAFT, OF ESSEN-ON-THE-RUHR, GERMANY.

GUN WEDGE BREECH-CLOSURE.

1,108,754.

Specification of Letters Patent.

Patented Aug. 25, 1914.

Application filed October 29, 1910. Serial No. 589,751.

To all whom it may concern:

Be it known that I, MAX HERMSDORF, a subject of the Emperor of Germany, and a resident of Essen-on-the-Ruhr, Germany, have invented certain new and useful Improvements in Gun Wedge Breech-Closures, of which the following is a specification.

This invention relates to wedge breech closures for guns, in which an operating lever swings in a groove.

The object of the invention is to relieve from the effect of firing that member of the operating lever, in breech closures of this class, which together with the groove, serves to move the wedge block.

In the drawing:—Figure 1 is a detail side elevation of the closed breech; Fig. 2 is a rear view partly in section on the line 2—2, Fig. 1; Fig. 3 is a detail with the breech in horizontal section and the block in full lines; and Figs. 4 and 5 are views similar to Fig. 3, showing the operating lever in two positions.

The wedge block B can be moved in the wedge hole of the breech A of the gun barrel by means of an operating lever C C¹ which, in the embodiment shown, is in the shape of a bell crank lever; said lever being mounted on the pivot or trunnion D, on the breech of the gun barrel. The arm C¹ engages an operating groove b¹ b² cut in the wedge block B by means of a roller E (see part, Fig. 2) journaled on a stud c² of the arm C¹. The part b¹ of the operating groove is curved concentrically with the axis of the trunnion D, while part b² of the groove runs obliquely to the direction of the movement of the wedge block B. The stud c² carrying the roller E is mounted on a boss c³ (Fig. 2) of the arm C¹. The boss c³ likewise engages the wedge block and is rounded on the face nearest the trunnion D, preferably to a cylindrical surface which registers with the circumference of the roller E, while its wall remote from the trunnion D presents a broad base or supporting face c⁴ curved concentrically to the axis of the trunnion D. When the breech is closed, the supporting face c⁴ bears against a face b³ of the wedge block, likewise running concentric to the axis of the trunnion D (Figs. 1 to 3).

In consequence of the arrangement of the face c⁴ on the boss c³, this latter extends beyond the roller E with two projections c⁵ and c⁶. Recesses b⁵ and b⁶ for these pro-

jections are cut in the side walls of the part b² of the operating groove.

Under the face b³ of the wedge block, a trough shaped recess b⁴ is provided in the corresponding wall of the part b¹ of the operating groove (see part, Fig. 4). The recess b⁴ has the same height as the roller E and lies exactly opposite it when the breech is closed.

In consequence of the above described arrangement of the recess b⁴, the roller E, when the breech is closed, has a clearance in the operating groove in such a direction, that pressure incident to discharge of the gun and tending to open the breech, cannot act upon the roller E and the stud c². Such a pressure will rather be transmitted immediately to the operating lever by the supporting faces b³ and c⁴.

The roller E and the stud c² are therefore relieved from the action of the discharge and consequently not liable to injury when the gun is fired. Such injuries would cause the roller to be jammed in the operating groove.

In opening and closing the breech the projections c⁵ and c⁶ move in the recesses b⁵ and b⁶ as stated.

It is obvious that this invention can also be applied to those wedge breech closures, in which the member of the operating lever coöperating with the operating groove, is constructed with a pin or the usual heart shaped piece instead of the herein described roller.

Claims—

1. In a gun wedge breech closure, the combination with the wedge block, an operating groove in one of the parts of the closure, of an operating lever journaled on the other part of the closure, a member on said lever engaging the groove to operate the closure, a supporting face on the lever adapted to bear against a supporting face on that part of the closure having the operating groove when the breech is closed, said supporting faces being so arranged that they may enter into engagement with each other without producing any movement of the wedge block, and means for completely relieving from the effect of firing the member of the operating lever engaging the operating groove.

2. In a gun wedge breech closure the combination with a wedge block, an operating

- groove in the wedge block, of an operating lever journaled on the breech of the gun barrel, a roller journaled on said lever and engaging the operating groove to operate 5 the closure, a supporting face on the operating lever adapted to bear against a supporting face on the wedge block when the breech is closed, said supporting faces being so arranged that they may enter into engagement with each other without producing 10 any movement of the wedge block, and a recess in one of the side walls of the operating groove for completely relieving the roller from the effect of firing.
- 15 3. In a gun wedge breech closure, the combination with a wedge block, a partly curved operating groove in the wedge block, having an open end, and a closed end, said groove having recesses in both of its side walls toward its closed end, and a recess 20 near its open end in its side wall remote from the axis of operation, and an operating lever adapted to engage with said groove and said recesses alternately.
- 25 4. In a gun wedge breech closure, the combination with the wedge block having a curved operating groove with an open end and a closed end, said groove being provided with a recess in one of its side walls near 30 its open end, of an operating lever journaled on the breech of the gun barrel, a roller journaled on said lever engaging said groove and registering with said recess when the breech closure is closed, to operate 35 the closure, the end of the lever extending beyond the periphery of the roller for engagement with said side wall of the groove, when the breech is closed whereby the lever acts to sustain the effect of the discharge of 40 the gun and protect the roller from injury.
5. In a gun wedge breech closure, the combination with a wedge block provided with a curved operating groove having an open end and a closed end and recesses in both
- of its side walls toward its closed end, and 45 at the same level, and a recess at a different level in one of its side walls near its open end, of an operating lever journaled on the breech of the gun and having an arm with a broad working surface, a roller journaled 50 on said lever so that its periphery does not extend beyond said working surface of the lever, said roller projecting within the operating groove, the broad working surface of the lever engaging the side wall of 55 the operating groove at its open end when the block is in closed position so as to act as a compression member between the block and the breech, the recess in the side wall of the groove near its open end, freeing the 60 roller from contact with the wall of the groove when the block is in closed position.
6. In a gun wedge breech closure, the combination with a wedge block provided with a curved operating groove having an open 65 end and a closed end, said groove being disposed obliquely to the direction of the movement of the block and provided with recesses in both of its side walls toward its closed end and at the same level, and a recess 70 at a different level in one of its side walls near the open end; of a bell crank lever journaled on the breech of the gun, one arm of which terminates in a broad end, projections extending from said broad end, a 75 roller journaled on said arm with its periphery not extending beyond the end of the arm, said roller projecting within the curved operating groove of the block and coöperating with said groove to open and 80 close the block.

The foregoing specification signed at Barmen, Germany, this 15th day of October, 1910.

MAX HERMSDORF. [L. s.]
